UNITED STATES PATENT OFFICE.

WALTER LUTZ, OF KNOXVILLE, TENNESSEE.

DISPLAY-RACK.

1,286,682.

Specification of Letters Patent.

Patented Dec. 3, 1918.

Application filed July 17, 1916. Serial No. 109,755.

To all whom it may concern:

Be it known that I, WALTER LUTZ, a citizen of the United States, residing at Knoxville, Park City, in the county of Knox and 5 State of Tennessee, have invented a new and useful Improvement in Display-Racks, of which the following is a specification, reference being had to the accompanying drawing.

10 My improvement relates particularly to display racks to be used for displaying various articles and commodities, including potted plants.

The object of the invention is to provide 15 such a structure in a form which is simple and strong and adapted to convenient folding to occupy small space and facilitate storage and crating for shipment.

In the accompanying drawings,

20 Figure 1 is a side elevation of a structure embodying my improvement;

Fig. 2 is a front elevation;

Fig. 3 is a section on the line, 3—3, of Fig. 2;

25 Fig. 4 is a section on the line, 4—4, of Fig. 2, looking toward the right;

Fig. 5 shows the rack folded, the view being in the same direction as in Fig. 1.

Referring to said drawings, 1, 1, are two 30 front standards, and 2, 2, are a pair of rear standards. One of each of said standards is placed at each end of the structure with one end resting on the floor while its upper end overlaps the adjacent standard, the

35 upper ends of the standards, 1, being placed between the upper ends of the standards, 2. The overlapping ends of the standards are joined to each other by horizontal pintles, 3, which may be rivets or screws or bolts. A

40 horizontal bar, 4, has its ends secured to the forward faces of the standards, 2, near the lower ends of said standards. Said bar constitutes a stay for the lower portions of said standards. At each end of the structure a

45 stay bar, 5, is secured to the outer face of the forward standard, near the lower end of the latter, by means of a pintle, 6, which may be a pin, screw, or bolt. The opposite end of each stay bar has in its upper edge 50 a notch, 7, adapted to receive the lower edge of the bar, 4. The two rear standards, 2, and the bar, 4, together constitute the rear support of the structure.

Between the front standards, 1, 1, are 55 three shelves, 8, having downward directed end pieces, 9. A screw or bolt, 10, extends

through each end piece into or through the adjacent standard to form a hinge whereby the shelf may turn on said standards.

Rearward of and parallel to each front 60 standard is a link bar, 11. A screw or bolt, 12, extends through each end piece, 9, into or through the adjacent link bar, 11. Each link bar, 11, extends below the stay bar, 5, and is coupled thereto by a screw or bolt, 13. 65 Oblique brace bars, 14, cross each other at the rear of the link bars, and have their ends lapping over and secured to the rear faces of the link bars by nailing or otherwise. 70

Each front standard and the adjacent link bar, 11, and the adjacent end pieces, 9, of the shelves, 8, are adapted to the movement similar to the movement of a parallel ruler, said standard and link bar corresponding to the bars of said ruler and the end pieces, 9, corresponding to the links of the ruler. 75

The bolts, 10, by which the end pieces, 9, are secured to the standards, 1, are placed 80 rearward far enough to bring a preponderance of the shelf load forward of said bolts, whereby the load tends to rotate the shelf, the forward portion going down and the rear portion going up. Such tendency to 85 upward movement of the rear portions of the shelves tends to lift the link bars, 11, and the upward strain on said bars places upward strain on the stay bars, 5, whereby the rear ends of said bars press upward against 90 the horizontal bar, 4, and keep said bar engaged in the notches, 7, in the stay bars, 5. In this manner the lower ends of the standards, 1 and 2, are firmly held in position. The diagonal brace bars, 14, hold the structure 95 against lateral swaying. The forward end of each stay bar, 5, is extended upward, and the pintle, 6, penetrates said extension. Said extension facilitates folding, as will be next described. Furthermore, to facilitate 100 such folding, the bolts, 12, penetrate the end pieces, 9, at a lower level than the level of the bolts, 10.

For folding, the forward edges of the shelves are first raised sufficiently to allow 105 the stay bars, 5, to descend at their rear ends sufficiently to disengage the bar, 4, from the notches, 7, of the bar, 5. If the bars, 5, are sufficiently elastic, their rear ends may be pressed downward until the bar, 4, and the 110 lower ends of the rear standards, 2, can be moved rearward. When the bar, 4, and the

stay bars, 5, have thus been released from each other, the shelves may be rotated to put them and the standards, 1, the link bars, 11, and the stay bars, 5, through a parallel-ruler 5 movement, until the shelves are in a common plane and the front faces of the link bars, 11, lie against the rear faces of the adjacent front standards, 1, and each stay bar, 5, lies lengthwise against the outer face of 10 the adjacent link bar, 11. This completes the folding of these parts. The rear standards, 2, are then turned rearward upward and forward across the other portions of the structure and downward on the hinge 15 formed by the pintles, 3, until each bar, 2, rests upon the outer face of the adjacent front bar, 1, and has what is normally its rear face flush with the front face of the adjacent front standard, 1. The bar, 4, is 20 so joined upon the bars, 2, as to enter the space between two shelves, 8, when the structure has been folded.

It will now be seen that the upward extension on the forward end of the stay bars, 25 5, permits said bars to lie rearward of the front standards, when the structure is folded, and leave room for the rear standards to overlap the front standards forward of the stay bars, 5, when the structure has 30 been folded. It will also now be seen that placing the bolts, 10 and 12, at different elevations in the end pieces, 9, permits the folding of the shelves into a plane which is parallel to the front standards and the link 35 bars while the latter lie against said standards.

When the structure is to be unfolded, the above-described movements are reversed in order and direction.

40 It is to be noted that the structure rests only on the lower ends of the front standards and the rear standards and not on the link bars, 11, the function of the latter being only to coöperate in controlling the shelf 45 and the stay bars, 5.

I claim as my invention,

1. In a structure of the nature described, the combination of front standards and a rear support, the standards being hinged 50 to the support at their upper ends, stay bars coupled by their forward ends to the lower portions of the front standards and having their rear ends adapted to enter into operative relation with the lower portions of the 55 rear support for staying the latter, shelves located between said front standards and hinged thereto, and link bars located rearward of the front standards and hinged to 60 said shelves and to said stay bars, substantially as described.

2. In a structure of the nature described, the combination of front standards and rear standards hinged to each other at their upper ends, a horizontal bar connecting said 65 rear standards, stay bars coupled by their

forward ends to the lower portions of the front standards and having their rear ends adapted to enter into operative relation with the horizontal bar, shelves located between said front standards and hinged thereto, and link bars located rearward of the front standards and hinged to said shelves and to said stay bars, substantially as described.

3. In a structure of the nature described, the combination of front standards and rear 70 standards hinged to each other at their upper ends, a horizontal bar connecting said rear standards, stay bars coupled by their forward ends to the lower portions of the front standards and having their rear ends 80 notched to receive said horizontal bar, shelves located between said front standards and hinged thereto, and link bars located rearward of the front standards and hinged to said shelves and to said stay bars, substantially as described.

4. In a structure of the nature described, the combination of front standards and a rear support, the standards being hinged to the support at their upper ends, said rear 90 support comprising a pair of standards and a horizontal bar connecting said rear standards at a proper height to fold between two shelves, stay bars coupled by their forward ends to the lower portions of the front 95 standards and having their rear ends adapted to enter into operative relation with the rear support for staying the latter, shelves located between said front standards and hinged thereto, and link bars located rearward of the front standards and hinged to 100 said shelves and to said stay bars, substantially as described.

5. In a structure of the nature described, the combination of front standards and a rear support, the standards being hinged to the rear support at their upper ends and said support comprising a pair of standards and a member connecting said standards and said rear support folding by upward and 105 forward and downward movement, stay bars coupled by their forward ends to the lower portions of the front standards and having their rear ends adapted to enter into operative relation with the rear support for 110 staying the latter and said bars folding by upward and forward movement, shelves located between said front standards and hinged thereto, and link bars located rearward of the front standards and hinged to 115 said shelves and to said stay bars, substantially as described.

6. In a structure of the nature described, the combination of front standards and a rear support, the standards being hinged to 120 the support at their upper ends, shelves located between said front standards and hinged thereto, stay bars in operative relation with the shelves to cause engagement with the rear support to stay the latter when 125 130

there is downward pressure on the forward portions of said shelves, substantially as described.

7. In a structure of the nature described, 5 the combination of front standards and a rear support, the standards being hinged to the support at their upper ends, shelves located between said front standards and hinged thereto, link bars located rearward 10 of the front standards and hinged to said shelves, stay bars coupled by their forward ends to the lower portions of the front standards and to said link bars whereby down-

ward pressure on the forward portions of said shelves tends to raise the rear portions 15 of said stay bars, and said stay bars having their rear ends adapted to enter, by upward movement, into operative relation with the rear support for staying the latter, substantially as described. 20

In testimony whereof I have signed my name, in presence of two witnesses, this 12th day of July, in the year one thousand nine hundred and sixteen.

WALTER LUTZ.
